[57] CLAIM

The ornamental design for a golf towel quick release hanger, as shown and described.

DESCRIPTION

FIG. 1 is a front elevation view of a golf towel quick release hanger showing my new design;

FIG. 2 is a right side elevation view, the left side elevation view being the mirror image thereof;

FIG. 3 is a rear elevation view thereof;

FIG. 4 is a top plan view thereof; and,

FIG. 5 is a bottom plan view thereof.

The shadow outlines of a portion of a towel in all the figures are for illustrative purposes only and form no part of the claimed design.
